UNITED STATES PATENT OFFICE.

GUSTAV MERTENS, OF DRESDEN, GERMANY.

ELECTROMAGNETIC RAIL-BRAKE.

1,123,343.

Specification of Letters Patent.

Patented Jan. 5, 1915.

Application filed July 31, 1912. Serial No. 712,453.

To all whom it may concern:

Be it known that I, GUSTAV MERTENS, a subject of the Emperor of Germany, residing at Dresden, in the Kingdom of 5 Saxony and Empire of Germany, have invented certain new and useful Improvements in Electromagnetic Rail-Brakes, of which the following is a specification.

My invention relates to improvements in 10 electromagnetic rail brakes in which a plurality of electromagnetic poles are disposed one behind the other in the direction of the rail. In brakes of this class as now constructed adjacent poles are separated from 15 one another by air gaps which are perpendicular to the longitudinal axis of the rail, so that the poles have a rectangular horizontal cross-section. The braking power of each pole depends on the cross-sectional area 20 of the head of the rail which is traversed by the magnetic flux. Therefore it can not be increased any more when the head of the rail is saturated with the magnetic flux. Therefore where it is desired to increase the 25 braking effect, it is necessary to increase the number of the poles.

The object of the improvements is to arrange the brake shoes or poles in such a way, that the braking effect is increased without 30 increasing the number of the poles. And with this object in view my invention consists in disposing the gaps between adjacent poles at an angle to the longitudinal axis of the rail, so that the face of the pole which 35 bears on the rail has the form of a trapezium or parallelogram. The magnetic flux is mainly perpendicular to the opposing faces of the poles which bound the air gaps. Therefore for the magnetic saturation of the 40 rail head cross sections are obtained the area of which is larger than the rectangular cross-section.

In order that my invention be more clearly understood two examples embodying the 45 same have been shown in the accompanying drawing in which the same letters of reference have been used in all the views to indicate corresponding parts.

In said drawing Figure 1, is a side view 50 of a rail and coöperating brake shoe, Fig. 2, is a horizontal cross-section taken along the line 2—2 of Fig. 1, and Fig. 3, is a similar cross-section showing a modification of the brake shoe.

55 Referring to the example illustrated in Figs. 1 and 2, on the rail *s* there is an elec-

tromagnetic brake *d* having alternately arranged positive and negative poles or brake shoes *p*. Between adjacent poles air gaps *z* are provided which are disposed obliquely 60 to the longitudinal axis of the rail. In the example illustrated in Fig. 2 the said air gaps are parallel to one another, so that the cross-sections of the poles are parallelograms, while in the example shown in Fig. 65 3 they are disposed at an angle to each other, so that the cross-sections of the poles are trapeziums.

The magnetic flux passes from one pole to the adjacent one in a direction perpendicular to the surfaces of the poles which bound the air gaps, that is in the example shown in Fig. 2 in the direction of the arrow. Therefore the section of the rail head which is crossed perpendicularly by the 75 magnetic flux and which determines by its area the saturation of the rail head has a breadth which is equal to the hypotenuse *f* of a triangle provided by the normal breadth *b* of the rail, and which is so much the 80 larger, the more the angle between *b* and *f* approaches 90 degrees. Thereby the degree of the magnetic saturation of the rail head can be regulated within large limits exclusively by the angle of the air gaps, or the 85 form of the horizontal cross-section of the poles, so that I obtain with the same number of poles a stronger braking effect, or the same braking effect with a smaller number of poles. By thus arranging the air 90 gaps at an angle to the longitudinal axis of the rail, the brake is not in the same degree liable to be held, if at the joints one of the rails projects above the adjacent one, or by 95 other obstructions, such as switches or crossings, and furthermore the brake gives way laterally when striking against projecting paving stones.

While in describing the invention reference has been made to a particular form of 100 the brake, I wish it to be understood, that my invention is not limited to the form of the brake shown in the drawing, and that it may be embodied in other types of electromagnetic brakes. For example the same 105 arrangement of the poles or air gaps may be used in electromagnetic wheel brakes having a plurality of brake shoes disposed one behind the other.

I claim herein as my invention:

1. Electromagnetic brake comprising a yoke, a plurality of poles connected with

said yoke and disposed one behind the other in the braking direction and separated at their ends by air gaps which are disposed obliquely to the braking direction and extend entirely from one side of the brake to the opposite one, and electric means to excite the brake, and adapted to move relatively to a member acting as an armature.

2. An electro-magnetic brake comprising
10 a plurality of poles disposed one behind the other in the braking direction and separated

at their ends by air gaps which are disposed obliquely to the braking direction and extend transversely from side to side of the brake; said poles having substantially the 15 same shape at their braking surfaces.

In testimony whereof I affix my signature in presence of two witnesses.

GUSTAV MERTENS.
